UNITED STATES PATENT OFFICE.

PETER GRAHAM MACGREGOR, OF NEW YORK, N. Y., ASSIGNOR TO PYRENE MANUFACTURING COMPANY, A CORPORATION OF DELAWARE.

DESIGN FOR A SYRINGE OR SIMILAR ARTICLE.

41,434.

Specification for Design.

Patented June 6, 1911.

Application filed March 17, 1911. Serial No. 615,127. Term of patent 7 years.

To all whom it may concern:

Be it known that I, PETER GRAHAM MACGREGOR, a citizen of the United States, and resident of the city of New York, county and State of New York, have invented a new, original, and ornamental Design for a Syringe or Similar Article, of which the following is a specification, reference being had to the accompanying drawing, forming part thereof.

The figure is an elevation of a syringe, showing my new design therefor.

The design comprises a casing having a cylindrical body portion provided with semi-spherically shaped ends and provided with a T-shaped handle at one end, substantially as shown in the drawings.

I claim:

The ornamental design for a syringe, or similar article, as shown and described.

PETER GRAHAM MACGREGOR.
